BURNER PORT LINING FOR SOAKING PIT AND METHOD OF CONSTRUCTION

Frank J. Pikus, Orem, Utah, assignor to United States Steel Corporation, a corporation of New Jersey

Application April 14, 1954, Serial No. 423,052

4 Claims. (Cl. 266—43)

The present invention relates to an improved gas port structure for bottom fired ingot soaking pits.

As may be seen in the patent to Morton, No. 2,124,888, the conventional bottom fired ingot soaking pit or furnace bottom having a centrally located burner port therein. A layer of loose granular material, such as coke breeze, on the refractory bottom forms the hearth of the soaking pit for supporting the ingots. The burner port lining projects above the level of the layer of loose material in order to prevent particles thereof from falling into the port. Frequently during the charging or drawing of ingots, which is accomplished by means of overhead crane means, the ingot being manipulated strikes the projecting portion of the burner port lining causing damage and premature failure thereof which necessitates shutting down the soaking pit until repairs can be made.

Ingot soaking pits are operated at temperatures sufficient to heat the ingots to their proper rolling temperature which ordinarily ranges from about 2150° to 2450° F. Since the burner port lining is exposed directly to the full temperature of the burner, it wears in a relatively short time and must be replaced at frequent intervals even when not damaged by physical impact.

Accordingly, it is an object of my invention to provide an improved burner port lining construction which is long wearing and highly resistant to damage by physical impact and a method of making the same.

It is a further object of the invention to provide an improved burner port lining construction which may be substantially prefabricated and easily and quickly installed in a bottom fire ingot soaking pit.

These and other objects will become more apparent after referring to the following specification and attached drawings, in which:

Figure 1 is a vertical sectional view of the prefabricated burner port lining of the invention before installation in a soaking pit;

Figure 2 is a view similar to Figure 1 showing the burner port lining of the invention completely installed in a soaking pit;

Figure 3 is a plan view of the bottom plate element of the invention with lifting eyes attached; and

Figure 4 is a sectional view taken on the line IV—IV of Figure 3 showing the mode of attachment of a lifting eye to the bottom plate.

Referring more particularly to the drawings, reference numeral 2 designates a bottom fired ingot soaking pit having a refractory brick bottom 4, a center burner port 6 and a hearth 8 consisting of loose granular material such as coke breeze or the like. Reference numeral 10 indicates generally the burner port lining construction of my invention.

The burner port lining 10 is prefabricated in a manner to be hereinafter described and consists of a steel bottom plate 12 having a center hole 14 therethrough and a brickwork construction 16 projecting upwardly from the bottom plate to a point above the level of the hearth 8. The center of the brickwork 16 consists of a filling of cast iron 18. The top 20 and the outer periphery 22 of the brickwork 16 are covered with a layer 24 of plastic refractory, such as plastic chrome or similar material.

The lining 10 is fabricated outside of the soaking pit by laying chrome-magnesite brick on the steel plate 12 to form two spaced vertical walls 26 around the hole 14 with a space 28 between the walls. The space 28 is then filled with the molten cast iron 18. I have found it preferable to arrange the brick in each of the walls 26 in staggered relation so as to define a vertically irregular space 28 for the purpose of firmly bonding the brick walls to the cast iron filling. It will be noted, however, that the brick in each of the walls may be arranged in a vertically straight line, if desired.

2

As shown in Figures 1, 3 and 4, lifting eyes 30 are affixed to the portion of the steel plate 12 immediately surrounding the hole 14 by means of nuts 32 which are welded to the plate. After the molten cast iron 18 has solidified in the space 28, the lining 10 is lifted by attaching the lift cables of an overhead crane (not shown) to eyes 30 and is deposited on the bottom of the soaking pit with the hole 14 communicating with the burner port 6 and the bottom plate 12 disposed below the top course of the refractory bricks forming the bottom 4 of the soaking pit. After the lining has been positioned in the soaking pit, the portion of the bottom plate 12 surrounding the hole 14 on which the lifting eyes 30 and the nuts 32 are affixed is burned off with a cutting torch. The cut-off line is indicated by dot and dash line "C" in Figure 3. This enlarges the diameter of the hole 14 so that it is substantially equal to the diameter of the burner port 6. As a final operation, a layer of plastic-chrome material is applied to the top 20 and outer periphery 22 of the brickwork 16.

As the molten cast iron filling 18 is poured, the iron penetrates between the courses of staggered brickwork slightly so that a strong bond is produced which is of greater strength than that created by the use of conventional mortar. The brickwork structure 16 is not bonded to the bottom plate 12 but remains in position by virtue of its weight.

While the soaking pit is operating, the heat from the burner has a tendency to liquify the surfaces of the cast iron filling causing it to react chemically with the abutting surfaces of the brickwork, thereby forming a magnesio-ferrite bond having greater strength and resistance to heat than cast iron alone.

While one embodiment of my invention has been shown and described, it will be apparent that other adaptations and modifications may be made without departing from the scope of the following claims.

I claim:

1. In a soaking pit having a refractory bottom containing a burner port, and a layer of loose material on said refractory bottom, the improvement therewith of a horizontally disposed steel plate surrounding said burner port below the level of said refractory bottom, a refractory brickwork on said plate extending upwardly to a point above said layer of loose material, said brickwork including two spaced walls of bricks defining a vertical space therebetween, a cast iron filling in said space, and a layer of plastic refractory around the top and outer periphery of said brickwork.

2. In a soaking pit having a refractory bottom containing a burner port, and a layer of loose material on said refractory bottom, the improvement therewith as defined by claim 1 characterized by each of said two spaced walls being comprised of a plurality of courses of staggered bricks defining a vertically irregular space therebetween.

3. In a method of constructing a burner port lining for a bottom fired furnace having a burner port in its bottom, the steps including providing a steel plate having a center hole therethrough with a diameter less than the diameter of said burner port, affixing a plurality of spaced hooks on said plate adjacent the inner edge thereof around said hole, building a brickwork of two spaced vertical walls of refractory brick on said plate around said hole adjacent the side of said plurality of hooks remote from said hole, filling the space between said walls with molten cast iron, lifting said lining by means of said hooks after the cast iron filling has solidified and depositing the lining on the bottom of said furnace with the hole in said plate communicating with the burner port, applying a layer of plastic refractory around the top and outer periphery of said brickwork, and enlarging said hole by removing the portion of the plate surrounding the hole on which the plurality of spaced hooks is affixed.

4. A method of construction as defined by claim 3 characterized by arranging the refractory bricks in the two walls in staggered relation to thereby define a vertically irregular space between the walls.
